US00D755853S

(12) **United States Design Patent**
Kang et al.

(10) **Patent No.:** US D755,853 S
(45) **Date of Patent:** ** May 10, 2016

(54) **DISPLAY SCREEN OR PORTION THEREOF
WITH ICON**

(71) Applicant: **Samsung Electronics Co., Ltd.**,
Suwon-si (KR)

(72) Inventors: **Yoon Kyung Kang**, Seoul (KR); **Tae
Hyoung Cho**, Seoul (KR)

(73) Assignee: **Samsung Electronics Co., Ltd.**,
Suwon-si (KR)

(**) Term: **14 Years**

(21) Appl. No.: **29/495,310**

(22) Filed: **Jun. 30, 2014**

(30) **Foreign Application Priority Data**

Jan. 3, 2014 (KR) 30-2014-0000515

(51) **LOC (10) Cl.** **14-04**

(52) **U.S. Cl.**

USPC **D14/492**; D14/489

(58) **Field of Classification Search**

USPC D14/485-495; D20/11, 15, 22-28, 31,

D20/32; 715/700-867, 961-978

CPC B60H 1/00; G06F 3/0481; H04L 41/22;

H04L 12/282

(57) **CLAIM**

We claim the ornamental design for a display screen or portion thereof with icon, as shown and described.

DESCRIPTION

The sole FIGURE is a front view of a display screen or portion thereof with icon showing our new design.

The dot dash lines in the FIGURE illustrate a boundary line and form no part of the claimed design.
